J. C. GREEN,
ROTARY TOOTH BRUSH,
APPLICATION FILED OCT. 1, 1914.
1,224,740.

Patented May 1, 1917.

UNITED STATES PATENT OFFICE.

JOHN C. GREEN, OF BURWELL, NEBRASKA.

ROTARY TOOTH-BRUSH.

1,224,740.

Specification of Letters Patent. Patented May 1, 1917.

Application filed October 1, 1914. Serial No. 864,504.

To all whom it may concern:

Be it known that I, JOHN C. GREEN, a citizen of the United States of America, residing at Burwell, in the county of Garfield 5 and State of Nebraska, have invented certain new and useful Improvements in Rotary Tooth-Brushes, of which the following is a specification, reference being had therein to the accompanying drawing.

10 This invention relates to a rotary tooth brush and has for its principal object the production of a tooth brush which is so formed as to allow the brush to freely rotate for producing a vertical motion when brushing 15 the teeth.

Another object of this invention is the production of a rotary tooth brush having its frame so formed as to provide an efficient gripping portion whereby the wing member 20 may be easily swung for rotating the brush.

A still further object of this invention is the production of a rotary tooth brush having a frame provided in its gripping portion with a compartment in which the operation 25 of the operative mechanism takes place whereby the hands of the user will be protected from injury when the wing is compressed inasmuch as the operating mechanisms are protected by the wing and gripping member.

With these and other objects in view, this invention consists of certain novel combinations, constructions, and arrangements 30 of parts as will be hereinafter fully described and claimed.

In the accompanying drawing:—

Figure 1 is a side elevation of the rotary tooth brush.

Fig. 2 is a central longitudinal section 40 through the device.

Fig. 3 is a section taken on the line 3—3 of Fig. 2, looking in the direction of the arrow.

Fig. 4 is a detailed perspective view of 45 the frame of the tooth brush, showing the spring carried thereby.

Fig. 5 is a transverse section through the brush illustrating the guard member therefor.

Fig. 6 is a detailed perspective view of 50 the operating shaft.

Fig. 7 is a fragmentary sectional view through a slightly modified form of the device illustrating the manner in which the 55 spring may be supported.

Fig. 8 is a fragmentary top plan view of the device as shown in Fig. 7.

Referring to the accompanying drawing by numerals, it will be seen that the device comprises in general a frame which is 60 formed of a one-piece structure as clearly shown in Fig. 4. This frame comprises a gripping portion 1 which is preferably triangular in shape to conform in shape to the hand of a person when the device is being 65 gripped. This gripping portion 1 has the barrel 2 formed integral thereon and from this barrel there extends the brush guard 3. The barrel 2 is provided with the longitudinal bore 4 communicating with the triangular compartment 5 formed within the gripping portion 1 of the frame. This compartment 5 is provided with an open side edge 6 and has one side portion thereof closed by means of the plate 7. It will be seen that 70 when this plate 7 is removed, the compartment 5 will be exposed for facilitating the assembling of the operating portions of the device. This plate 7 is held in a fixed position upon the gripping portion 1 as clearly 75 shown in Fig. 1 by means of the retaining screws or tacks 8 which pass therethrough and engage the gripping portion. Thus it will be seen that the compartment 5 is entirely inclosed with the exception of the 80 open portion 6 at one side edge of the frame.

An operating shaft 9 is positioned within the bore 4 so as to extend into the compartment 5. This shaft 9 is provided with a conical body 10 in which there is formed 90 the threaded opening 11. This body 10 is so positioned as to extend into the inner portion of the brush guard 3 and is adapted to detachably engage the stem 12 of the brush 95 13 since the stem 12 is threaded into the threaded opening 11. It will be seen that the brush 13 is guarded upon its rear side by means of the brush guard 3 which is formed so as to fit snugly upon the outer periphery of the brush as clearly shown in 100 Fig. 5. The opposite end of the shaft 9 extends through the aperture 14 formed in the gripping portion 1 and this aperture 14 communicates with the socket 15. The shaft 9 is provided with a cap 16 fitting within 105 the socket 15 and by means of this cap fitting within the socket 15 and the body 10 being positioned adjacent the outer end of the bore 4 of the barrel 2, it will be seen that the shaft will be held against longitudinal 110

movement after the device has been assembled. By constructing the device as above set forth, it will be seen that upon the rotation of the shaft 9 rotary movement will be imparted to the brush 13 whereby when a person is brushing the teeth a vertical brushing movement will be imparted which is more beneficial than the usual horizontal movement inasmuch as an even pressure may be maintained upon all portions of the teeth. It will further be noted that a pinion 17 is carried by the shaft 9 and partially fits within the cut-out portion 18 formed within the compartment 5 for the accommodation of the pinion.

In order to operate the shaft 9 there is provided a wing 19 which is concavo-convex in cross-section and has its ear portions 20 formed in parallel spaced relation so as to fit upon either side of the barrel 2 adjacent the gripping portion 1 for allowing the pivot pin 21 to be passed through the ears and through the frame for pivotally mounting the trigger upon the frame. A flat spring 22 is held upon the frame by means of the screw 23 and this spring 22 is formed so as to partially overhang the opening 6 in the compartment 5 and to extend outwardly from the frame. This spring 22 bears upon the inner portion of the wing 19 for normally urging the wing outwardly as is clearly disclosed in Figs. 1 and 2. An arc rack bar 24 is provided with laterally extending lips 25 through which the rivets 26 may be passed for fixedly retaining the rack bar in engagement with the wing 19. The free end of this rack bar always remains within the compartment 5 so as to engage the pinion 17 as disclosed in Fig. 3.

It will be noted by carefully referring to Fig. 3 that the plate 7 is placed at a spaced distance from the pinion 17 so as to accommodate the rack bar 24. It will be noted however, that the rack bar will rotate the pinion 17 as it passes thereover while it will ride evenly upon the plate 7. In this manner it will be seen that the rack bar 24 will be held against lateral or torsional movement when in operation.

When this device is in operation it will normally assume the positions disclosed in Figs. 1 and 2. The gripping portion 1 and the wing 19 may be easily gripped at which time the brush 13 is to be placed in engagement with the teeth. By compressing the wing 19, it will be swung toward the gripping portion 1 so as to close the opening 6 of the compartment 5 as is disclosed in Figs. 2 and 3, in dotted lines. As the wing 19 is swung upon the pivot member 21 it will be seen that the rack bar 24 will cause the pinion 17 to rotate the shaft 9 and in this manner rotary movement will be imparted to the brush 13. As soon as the pressure is removed from the wing 19 however, the force

of the flat spring 22 will urge the wing outwardly and therefore will rotate the shaft and brush in the opposite direction to that in which they are originally rotated.

By referring to Figs. 7 and 8 it will be seen that the gripping portion 1' is provided with the barrel 2' through which the shaft 9 extends. The compartment 27 in this form of the device is also closed upon its side portions by means of the closure plate 28 having the laterally bent slanting lip 29 extending transversely across the gripping portion 1' as clearly shown in Fig. 8 whereby the plate will be firmly held in engagement with the gripping portion, independent of the secondary securing means. The flat spring 22' extends downwardly into the notched portion 30 so that when the spring 22' is positioned therein it may be retained by means of the pin 31 so as to bear upon the lip 29. By reinforcing the spring by means of the lip 29 it will be seen that when the spring is swung by means of the wing member it will bear upon the lip so as to prevent injury to the portion of the gripping member adjacent which the pressure of the spring when being swung takes place.

It will of course be seen that by forming the compartment and placing the guard and pinion thereon within the compartment and by forming the wing member so as to be concavo convex in cross section, the wing member may be swung so as to fit snugly upon or straddle the gripping member while the rack bar fixedly secured within the wing will rotate the shaft by means of the pinion.

From this construction it will be seen that any possible injury to the hands of the user is prevented inasmuch as all of the operating elements of the device are efficiently protected and consequently cannot be touched as the device is operating.

What I claim is:—

1. A rotary tooth brush of the class described comprising a grip portion, said grip portion being substantially triangular in shape, a rotary brush supporting shaft passing through said grip portion, a wing pivotally secured to said grip portion, and means carried by said grip portion and co-operating with means upon said rotary brush supporting shaft for rotating said brush supporting shaft as said wing is swung upon said grip portion, said grip portion being broader toward its rear end than toward the forward end thereof for resisting the slipping of said grip portion from the hand of an operator while the same is in use.

2. As a new article of manufacture, a rotary tooth brush comprising a body, said body terminating in a grip portion, said grip portion being gradually enlarged toward the rear end thereof, a wing pivotally secured to said body, a rotary brush supporting shaft, and means carried by said

wing and coöperating with means upon said rotary brush supporting shaft for facilitating the rotation of said rotary brush supporting shaft as said wing is swung upon 5 said grip portion, said grip portion constituting means for resisting the slipping of the same from the hand of the operator while in operation.

3. A rotary tooth brush comprising a body, 10 a flat grip portion carried by one end of said body and provided with a substantially V-shaped pocket formed therein, said grip portion being widened toward the rear end thereof for producing a substantially tri-

angular shape grip portion, a wing pivot- 15 ally secured to said body, and means carried by said wing and coöperating with means upon said rotary brush supporting shaft for working in said substantially V-shaped pocket for rotating said rotary brush sup- 20 porting shaft as said wing is swung upon said grip body.

In testimony whereof I hereunto affix my signature in presence of two witnesses.

JOHN C. GREEN.
